UNITED STATES PATENT OFFICE.

CHARLES CARROLL ARMSTRONG, OF HUNTINGTON, WEST VIRGINIA.

ELECTRIC HEATING ELEMENT FOR STOVES.

Application filed March 18, 1924. Serial No. 700,046.

To all whom it may concern:

Be it known that I, CHARLES C. ARMSTRONG, a citizen of the United States, and resident of Huntington, in the county of Cabell and State of West Virginia, have invented certain new and useful Improvements in Electric Heating Elements for Stoves, of which the following is a specification.

10 The invention concerns heating elements used for instance in electric stoves in which the body of the element is made of heat resisting material as clay molded and baked, and furnishes the support for the wire heating coil.

In the drawings—

Figure 1 is a plan view of the body of a heating element made according to my invention, only a small portion of the wire 20 heating coil or electric conductor being shown.

Fig. 2 is a sectional view of Fig. 1.

Fig. 3 is a cross sectional view of a portion of the clay body of the heating element with its coil retaining projection partly formed.

Fig. 4 is a cross sectional view similar to Fig. 3 with the coil retaining projection completely formed and the electric heating coil in place.

In these drawings 1 indicates the main body of the heating element, which is molded from material of high heat resisting qualities, as for instance, clay. The body 35 is in the form of a circular plate having a groove 2 in its upper face, this preferably being of spiral form. This groove is adapted to receive the coil of wire which receives the electric current and furnishes the 40 heat for cooking.

In order to retain the heating coil in place, projections 3 are formed as a part of the molded body and these projections extend from the upper portions of the wall 45 of the groove transversely and thus overhang the main portion of the groove in which the heating coil is seated. In the best form of the invention the lugs extend only part way across the groove, and opposite each projection there is formed in the other wall of the groove a recess 4 conforming generally in shape to the curved contour of the projection, so that the coil can be inserted into place through the gate thus 50 formed without undue stretching or distortion and without having to drag the coil

along the groove. The coil is slipped into place under the projection by introducing it through the recess. There are a considerable number of these projections and recesses and they may be located out of radial alignment as shown.

In the formation of these projections it is one object of the present invention to avoid the occurrence of openings through the plate below these projections which have been necessitated in a prior process in order to provide these overhanging projections in the act of molding the plate. In this prior process it has been the practice to 70 mount pins on the lower mold section of the same or greater cross sectional area as the area of the projections. These pins formed the means for shaping the under side of the lugs or projections.

When the molded body is removed from the mold openings are left at the points where the pins occur and these openings extend entirely through the body of the heating member from the bottom of the 80 groove to the lower face, and are objectionable because of the loss of heat therethrough.

They are objectionable also because of 85 weakening the body of the heating element.

In carrying out the present improvement, the overhanging projection is provided by first molding the projection like a rib extending vertically the full depth of the grooves as indicated at 5, and thereafter, 90 and while the material is still soft or in "green" condition, undercutting this vertical rib as shown by the dotted line in Fig. 3, with a small milling cutter mounted on a flexible shaft. This milling cutter is of 95 proper shape that after performing its work the projection will have assumed the form shown in Fig. 4, ready to receive the coil of conducting wire beneath it. The body of the plate is left intact and continuous 100 at the bottom of the groove, no opening being present at the point below the overhang and hence the radiation of heat from the coil will be entirely upward, there being no openings for its wasteful escape 105 downwardly.

After the undercutting is done the body is ready to be baked to harden the material.

I claim:

1. A heating element for electric stoves and the like comprising a heating coil, a

- body spirally grooved on its upper face with overhanging projections at intervals along the groove extending transversely of the groove at the upper part thereof, the
- 5 wall of the groove opposite said projections being recessed to form gates for the introduction of the heating coil below said projections, the width of the groove being substantially the same as the diameter of the coil.
2. A heating element for electric stoves and the like comprising a heating coil, a body spirally grooved on its upper face with overhanging projections at intervals
- 15 along the groove extending transversely of the groove at the upper part thereof, the wall of the groove opposite said projections being recessed to form gates for the introduction of the heating coil below said
- 20 projections, said projections extending from

the side of the groove which is nearest the center of the element, the width of the groove being substantially the same as the diameter of the coil.

3. The herein-described process of making heating elements consisting in molding a body of heat resisting material grooved on its upper side and with vertical ribs extending from one wall partly across the groove, then undercutting the vertical ribs to form projections overhanging the bottom of the groove, leaving the mass of the body below the projections continuous along the bottom of the groove and continuous with the rest of the mass of said body, substantially as described.

In testimony whereof, I affix my signature.

CHARLES CARROLL ARMSTRONG.
